ICE CREEPER

Nils Albin Nordin, Anchorage, Territory of
Alaska

Application March 28, 1950, Serial No. 152,424

3 Claims. (Cl. 36—61)

1

This invention relates to ice creepers of a type adapted to be worn on the feet over the shoes and an object of this invention is to provide an ice creeper having a spike carrying portion which is pivotally movable between an operative position underneath the shank portion of a shoe sole and an inoperative position in which it extends upwardly alongside of the shoe.

Another object is to provide an ice creeper for use on the foot which has a spike carrying portion adapted to be quickly and easily moved between an operative position and a retracted position without removing the ice creeper from the foot thus making it possible to have the benefit of the spikes under the shoe sole when walking on ice and slippery surfaces and to fold said spikes out of the way without removing the ice creeper from the foot when walking on non-slippery surfaces such as floors and sidewalks.

Another object of this invention is to provide an ice creeper which is quickly and easily adjustable to foot wear of different size and which can be worn over shoes, boots, pacs, overshoes and the like.

Other objects of the invention are to provide an ice creeper which is simple in construction, not expensive to manufacture, easy to put on and take off and convenient to wear when a person is walking on slippery surfaces part of the time and non-slippery surfaces part of the time.

Other objects of this invention will be apparent from the following description taken in connection with the accompanying drawings.

In the accompanying drawings Figure 1 is a plan view of an ice creeper constructed in accordance with this invention showing the top side of a footplate and the bottom or spike carrying side of a spike carrying plate and with the two plates shown in a common plane.

Fig. 2 is an edge view of the same looking in the direction of broken line 2—2 of Fig. 1.

Fig. 3 is an edge view of this ice creeper as the same may appear when the spike carrying folding plate thereof is in an operative position underneath the footplate and further showing fragments of straps connected with the footplate.

Fig. 4 is a fragmentary edge view of this ice creeper showing the spike carrying folding plate thereof in a raised or inoperative position.

Fig. 5 is a fragmentary side elevation, on a smaller scale than Figs. 1 to 4 inclusive, showing this ice creeper applied to a shoe, the ice creeper being shown in end elevation.

Fig. 6 is a fragmentary perspective view show-

2

ing a strap attachment bracket and a fragment of a footplate.

Fig. 7 is a detached perspective view showing another strap attachment bracket.

Fig. 8 is a bottom plan view showing a spike carrying plate of modified form which is provided with detachable spikes which can be replaced when worn or damaged.

Fig. 9 is a fragmentary sectional view taken on line 9—9 of Fig. 8 and showing a detachable spike member.

Fig. 10 is a detached side view showing a strap attachment bracket of modified form.

Fig. 11 is a fragmentary plan view showing a footplate having a slot adapted to adjustably receive the strap attachment bracket shown in Fig. 10, a rivet member of the strap attachment bracket being shown in said Fig. 11.

Like reference numerals designate like parts throughout the several views.

In Figs. 1 to 7 inclusive 15 designates a metal footplate having on one end a fixed upwardly extending strap receiving bracket 16 which is provided with a transverse slot 17 to receive a strap 18, Fig. 3. Preferably the bracket 16 is inclined outwardly as shown, whereby when said footplate is worn crosswise of a shoe sole under the shank portion thereof the bracket 16 will conform approximately to the slope of the side of the foot. Preferably the outer face of the bracket 16 is provided with a groove 20, Fig. 6, which extends from the bottom of said bracket upwardly part way to the top thereof and which terminates in a recess 21 of greater depth than the groove. The groove 20 and recess 21 cooperate to releasably hold a spike carrying folding plate 22 in an operative position, as more fully hereinafter explained.

A longitudinal slot 23 is provided in the footplate 15 near the end thereof opposite the bracket 16 and cooperates in supporting an adjustable strap receiving bracket 24, Fig. 7. The bracket 24 has a slot 25 to receive a strap 26 which cooperates with the strap 18 in securing the footplate 15 to the foot of the user. The bracket 24 has an integral base portion 27 which is disposed substantially at right angles to said bracket 24 and is connected with the bracket 24 by a neck part 28. The neck part 28 is narrow enough to fit within and cooperate with the slot 23. Two notches 29 are provided at opposite sides of the neck part 28. A block or plate 30 is welded or otherwise rigidly secured to the base part 27 in line with the neck part 28. This block 30 operates in the slot 23 of the footplate 15 and pre-

vents the bracket 24 from turning sidewise when said bracket is in an upright position relative to the footplate. By tilting the bracket 24 substantially parallel to the footplate 15 and turning said bracket at the proper angle it is possible to pass the base part 27 through the slot 23 and either engage the bracket 24 with the footplate 15 or disengage the same from said footplate 15. The bracket 24 is self adjusting to feet and shoes of different size within the limits afforded by the slot 23.

The spike carrying plate 22 is pivotally connected, as by a hinge pin 31, with the end portion of the footplate 15 adjacent the slot 23. Preferably the hinge pin 31 is secured, as by cross pins 32, to the spike carrying plate 22 so that the hinge pin 31 can be used as a means to hold the spike carrying plate 22 in the raised and inoperative position in which it is shown in Fig. 4. A head 33 is rigid with the hinge pin 31 and has a flat side 34 which is adapted to be engaged by a flat spring 35 when the spike carrying plate 22 is in the raised position shown in Fig. 4. This spring 35 will yieldingly hold the spike carrying plate 22 in the raised position and will permit said plate 22 to be quickly and easily lowered at any time. The flat spring 35 is secured to the foot plate 15.

The spike carrying plate 22 carries a plurality of spikes 36 which may be of triangular shape and may be formed by punching out and bending outwardly parts of the plate 22 along the edges thereof. Four spikes 36 are shown but obviously a greater or less number of said spikes may be provided.

Also I may use a spike carrying plate 37, see Figs. 8 and 9, which has spikes 38 removably and replaceably secured thereto as by welding nuts 39 to said plate 37 and threading the spikes 38 into these nuts 39.

The outer end portion of the spike carrying plate 22 is bent substantially at right angles to said plate 22 to provide a latch portion 40 and this latch portion 40 has an out turned end portion 41 to facilitate its disengagement from the footplate 15 as hereinafter explained. The latch portion 40 has a rib 42 and further has a rounded knob 43 at the upper or outer end of the rib 42. The rib 42 and knob 43 are adapted to fit within the groove 20 and recess 21 respectively in the upstanding strap receiving bracket 16 when the spike carrying plate 22 is in the operative position shown in Fig. 3. The rib 24 cooperates with the groove 20 to prevent relative sidewise movement of the two plates 16 and 23 and thus relieves the hinge pin and hinge structure of much strain. The knob 43 snaps into the recess 21 and the plate 22 is thereby prevented from swinging downwardly while in use. The user can disengage the knob from the recess 21 by pressing downwardly with one foot on the out turned end portion 41 of the latch member 40 worn on the other foot.

Figs. 10 and 11 show an adjustable strap receiving bracket means of modified form comprising a footplate 44 provided with a slot 45 having corrugated or wave like edges which make the said slot 45 narrower at some places than it is at other places. An enlarged opening 46 is provided at one end of said slot 45. A strap receiving bracket 47 has a base 48 provided with a fixed rivet 49 having a head 50. The rivet 49 is flattened on preferably two opposite sides, as shown in Fig. 11. The head 50 can be passed through the enlarged opening 46 thus making the bracket

47 easy to apply to and remove from the footplate 44. When the rivet 49 is in the position in the footplate 44 shown in Fig. 11 the bracket 47 will be crosswise of said footplate and will be restrained against movement along the slot 45. When the bracket 47 is turned parallel to the slot 45 then the rivet 49 is movable or adjustable along the slot 45. This bracket 47 is not self adjusting but it can be manually adjusted along the slot 45 when the footplate is detached from the foot and said bracket 47 be held in any position into which it is adjusted.

The spike carrying plate of this device can be quickly and easily moved from and operative to an inoperative position and vice versa thus making it convenient and time saving for wear when the user is changing frequently from icy to non-icy surfaces.

The foregoing description and accompanying drawings clearly disclose preferred embodiments of this invention but it will be understood that this disclosure is merely illustrative and that changes may be made within the scope and spirit of the following claims.

I claim:

1. A folding ice creeper comprising a footplate positioned crosswise beneath the shank portion of a shoe; two spaced apart upstanding strap receiving brackets on said footplate extended upwardly along opposite sides of a shoe; strap means connected with said two upstanding brackets; a spike carrying plate having one end portion thereof hinged to one side of said footplate to selectively position said spike carrying plate between a position at right angles to the footplate and a position in face to face relation with the footplate; and a plurality of spikes of triangular shape integral with said spike carrying plate and perpendicular to said spike carrying plate and positioned along lateral edges of said spike carrying plate.

2. A folding ice creeper applicable to a shoe worn on the foot comprising a footplate positioned crosswise beneath the shank portion of the shoe; two spaced apart upstanding strap receiving brackets on said footplate extended upwardly at opposite sides of the shoe; strap means connected with said brackets; a spike carrying plate having one end portion thereof hinged to one side of said footplate for folding movement of the spike carrying plate between a position underneath the footplate and an upwardly extending position at one side of the shoe so that it will be alongside of the shoe when the ice creeper is on a shoe; spikes carried by said spike carrying plate; and spring means yieldingly holding said spike carrying plate in an upwardly extending position relative to said footplate.

3. A folding ice creeper comprising a footplate positioned crosswise beneath the shank of a shoe; two spaced apart upstanding strap receiving brackets on said footplate extended upwardly at opposite sides of the shoe; strap means connected with said brackets; a spike carrying plate having one end portion thereof hinged to one side of said footplate for folding movement of the spike carrying plate between an operative position in face to face relation with the footplate and an inoperative position at right angles to the footplate; spikes carried by said spike carrying plate; spring means yieldingly holding said spike carrying plate perpendicular relative to said footplate; an approximately perpendicular integral latch portion provided on the outer end portion of said spike carrying plate and positioned alongside of

one of said upstanding strap receiving brackets when said spike carrying plate is face to face with said footplate; and interfitting projection and recess means provided on the adjacent faces of said latch portion and the upstanding bracket engaged thereby, whereby said footplate and said spike carrying plate are releasably latched in face to face relation and relative sidewise movement of said two plates is prevented.
